WELL FLOW DEVICE

Lyndon L. Hartman, Dallas, Tex.

Application May 17, 1946, Serial No. 670,502

15 Claims. (Cl. 103—232)

1

This invention relates to new and useful improvements in flow control devices, and particularly in well flow devices.

As is well known, a lifting medium, such as gas or air, has come into widespread use as a means of lifting well liquids upwardly through a well tubing or conductor. The lifting medium or gas is confined in the annular space between the well tubing and the well casing and is admitted into the tubing as needed to raise the well liquids. Ordinarily, the admission of the lifting fluid into the tubing is controlled by a single valve which is actuated by the pressure differential thereacross, that is, one side of the valve is exposed to the lifting fluid and its opposite side is exposed to the pressure of the liquid within the tubing. Thus, when the well liquid pressure reaches a point sufficient to overcome the lifting fluid pressure holding the valve closed, said valve is opened to admit the lifting fluid to the tubing and raise the liquid. However, the single valve does not satisfactorily change the volume of lifting fluid after the liquid column is in motion and therefore, a smooth lifting action is not obtained. It is obvious that once the liquid column is in motion, less volume of lifting fluid is required to keep it moving upwardly than was needed to begin flow and in order to conserve the lifting fluid, as well as to provide a smoother action, it is desirable that the volume of admitted lifting fluid be reduced.

Another disadvantage of the single differentially actuated valve is that so long as the lifting fluid pressure in the annular space outside the tubing remains substantially constant, the operation is satisfactory because then the pressure of the liquid must build up to substantially the same point each time to open the valve. However, in instances where the annular space outside the tubing is in communication with sub-surface formations, pressure from such formations is added to the lifting fluid pressure to increase the same. When this occurs, the pressure differential across the main valve necessary to open said valve may remain the same but the pressures on opposite sides of said valve are changed. In other words, assuming that a differential of 50 pounds across said valve is required to open the valve and that the lifting fluid pressure is normally 300 pounds, then the well liquid pressure would have to reach 350 pounds to open the valve. If the lifting fluid pressure built up to 350 pounds due to the addition of formation pressure, the well liquid pressure would have to attain 400 pounds. It thus becomes obvious that continued

2

increase in the lifting fluid pressure could build up to a point where the well liquid pressure could not overcome it and the valve would be rendered inoperative. For this reason, it is essential that the pressure of the lifting fluid in the annular space outside the tubing be controlled and maintained substantially constant.

It is one object of the present invention to provide an improved well flow device for controlling the admission of a lifting fluid, such as gas or air into a liquid column within a well tubing or conductor and which has its valve mechanism so constructed that the volume of lifting fluid is automatically varied during operation of the device and in accordance with the changing conditions and requirements, whereby more efficient lifting of the well liquid is accomplished.

An important object of the invention is to provide an improved well flow device wherein a plurality of valve elements are mounted for individual actuation, with each element being operated under a predetermined pressure differential which operating differential is different from that of the others, whereby the valve elements close progressively or in succession at spaced intervals and in accordance with the changing differential produced by the flowing well liquid column; the successive actuation of the valve elements effecting a change of volume of lifting fluid being admitted to the liquid column, whereby the required volume of lifting fluid is introduced into the liquid column throughout the entire cycle of operation of the device.

Still another object of the invention is to provide an improved well flow device, of the character described, wherein a plurality of valve elements are mounted for actuation by the differential in pressure of the lifting fluid and the pressure of the liquid column to be lifted; each valve having associated therewith a resilient means, such as a spring, which controls or sets the differential at which said valve is to operate and the resilient means of each valve being different from the resilient means of the others so that the valves are actuated by various predetermined pressure differentials, said valve elements being mounted to telescope one within the other whereby a simple compact device is had.

A further object of the invention is to provide a valve device having valve elements each of which is arranged to operate upon a pressure differential thereacross, with the differential actuating one valve element being dissimilar from the differentials which operate the other elements, whereby a change in volume of the fluid con-

trolled by the device is affected as the valve elements progressively operate; the device being particularly adapted for use as a well flow device for admitting lifting fluid into a well liquid column but being so arranged that it may be employed for controlling the flow of any fluid in other types of mechanisms.

An important object of the invention is to provide an improved well flow device which is so constructed that its valve elements may be re-arranged in another position and in such event the device will operate to maintain the pressure differential required to actuate the valve, substantially constant regardless of possible changing pressure conditions which may occur on one side of the device and which would normally vary the differential necessary to operate said valve.

Another object of the invention is to provide an improved flow device, of the character described, wherein a main valve, which controls the admission of lifting fluid into the well liquid column, has one side exposed to the lifting fluid pressure and its opposite side exposed to the well liquid pressure whereby said valve is actuated by a predetermined differential between said pressures; the device also including means for maintaining the lifting fluid pressure which acts on one side of the valve substantially constant, whereby the pressure of the well liquid column will build up to substantially the same point within the well conductor before the valve is actuated to admit lifting fluid to said liquid column.

A particular object of the invention is to provide an improved well flow device having two valve elements which may be arranged to be actuated by a pressure differential thereacross, with the differential necessary to actuate one valve element being different from the differential required to actuate the second valve, whereby the device functions as a lifting fluid device which automatically varies the volume of admitted fluid during its operation; said valve elements being adapted to be rearranged so that one functions as a differentially actuated valve for controlling the admission of the lifting fluid while the other acts merely as a relief or stabilizing valve so as to prevent the pressure acting on one side of the first valve from exceeding a predetermined point, whereby efficient operation of said first valve is assured.

The construction designed to carry out the invention will be hereinafter described together with other features of the invention.

The invention will be more readily understood from a reading of the following specification and by reference to the accompanying drawing, wherein an example of the invention is shown, and wherein:

Figure 1 is a view, partly in section and partly in elevation of a well bore having a well tubing or conductor extending therethrough and having a well flow device, constructed in accordance with the invention, mounted in said tubing.

Figure 2 is an enlarged, transverse, sectional view of the flow device, showing the valve elements functioning as a lifting fluid control device, with both valves in an open position.

Figure 3 is a similar view, with the outer valve closed and the inner valve open.

Figure 4 is a similar view with both valve elements closed.

Figure 5 is a horizontal, cross-sectional view, taken on the line 5—5 of Figure 3, and

Figure 6 is a view similar to Figure 2, and illustrating the valve elements rearranged, whereby

one element functions as the lifting fluid control and the other functions as a stabilizing valve.

Although the improved valve device may be employed for controlling the flow of any desired fluid in various mechanisms, the device will be described herein as controlling the admission of a lifting fluid into a well conductor, whereby the liquid column in said conductor may be lifted to the surface; however, this is only one application of the invention.

In the drawings, the letter A designates a well bore having a well casing 10 therein. A well tubing 11 extends downwardly through the casing 10 and has its upper end supported in the usual casing head 12 which is mounted on the upper end of said casing. The lower end of the well tubing has the conventional well screen, through which the well fluids are admitted into said tubing, attached thereto.

The improved well flow device B is arranged to be connected in the tubing or well conductor 11 and is located at the desired elevation or level in accordance with the particular well conditions.

If desired, a plurality of the devices set to operate under different pressure conditions, as will be hereafter disclosed, may be disposed at various elevations in the tubing. The valve device is arranged to control the admission of a lifting fluid such as gas or air into the well tubing or conductor 11 so that such fluid may raise or lift the well liquids upwardly through said tubing to the surface. The invention will be herein described as operating with an auxiliary lifting fluid, such as gas, but it is noted that the lifting

fluid may be gas from a sub-surface formation which is conducted into the well casing. The auxiliary lifting fluid or gas is conducted to the annular space between the well casing 10 and the well tubing 11 through an inlet pipe 14 which is connected to the casing 12. With the arrangement illustrated, the lifting fluid is introduced into this annular space and fills said space, with the pressure of the lifting fluid being maintained at a desired point. The presence of a lifting fluid

under pressure within the annular space surrounding the well tubing causes the well liquids which flow from the formation to enter the lower end of the well tubing and rise upwardly to a normal standing level within said tubing. It will be noted that the lower portion of the annular space is not packed off from the formation with the result that any gas within said formation may enter said annular space. The entrance of this gas may act to increase the pressure within the annular space and the flow device B, as will be explained, not only controls the admission of the lifting fluid into the well tubing but may be slightly modified to function to maintain the pressure of the lifting fluid within the annular space substantially constant, regardless of the volume of gas or increased pressure which may result from entry of fluids from the formation into said annular space.

The construction of the valve device B is clearly illustrated in Figures 2 to 5 and said device includes a tubular housing 15 comprising an upper section C and a lower section D connected together by a coupling or bushing 16. The housing is formed with a radially extending boss 17 having a threaded axial pin 18 integral therewith which is adapted to be screwed into an opening 19 formed in the wall of the well tubing 11 and in this manner the housing is connected to and supported by said tubing. The bore 20 of the housing communicates with the interior of the well

65

66

67

68

69

70

71

72

73

74

75

tubing through an inclined radial port 21 which extends through the boss 17 and pin 18. The upper end of the housing is closed by a cap member or plug 15a which threads into said housing.

The lower end of the housing 15 has a closure 22 threaded thereon and as is clearly shown in Figure 2 said closure has inlet openings 23 therein. The coupling 16 has an axial bore 16a extending entirely therethrough and it is apparent that a flow from exteriorly of the housing may occur through the inlet openings 22, bore 16a of the coupling, bore 20 of the housing and finally into the well tubing 11 through the radial port 21.

An annular valve seat 24 is formed on the lower end of the coupling 16 and surrounds the lower portion of the bore 16a thereof. A tubular valve element 25 is movable axially through the bore 16a of the coupling 16 and has its ends projecting beyond the upper and lower ends of said coupling. The lower end of said valve element has a valve head 26 integral therewith and this head includes a conical seating surface 27 which is adapted to engage a valve seat 24 of the coupling 16; when the valve element is in a seated position, flow through the bore 16a of the coupling is closed. The valve element 25 and head 26 are formed with an axial bore 28 extending entirely therethrough and the upper portion of the element is provided with radial stop lugs or projections 29 which prevent downward displacement of the element from the bore 16a of the coupling. If desired, a valve head (not shown) could be provided at the upper end of the element to prevent reverse flow through the bore 16a.

The valve element 25 is normally urged downwardly toward an opened or unseated position by a coil spring 30 which is located within the bore 20 of the housing 15 and which has its lower end engaging the upper end of the valve element. The upper end of the spring 30 is confined within an annular recess 31 which is formed in the underside of an adjusting bushing 32, the latter being threaded into the upper end of the housing below the cap or plug 15a. The spring 30 is of a predetermined pressure and adjustment thereof may be accomplished by adjusting the bushing 32 inwardly and outwardly of the upper portion of the bore of the housing. The upper end of the valve element 25 is exposed to the well liquid pressure in the tubing while its lower end is exposed to the lifting fluid pressure exteriorly of the housing, whereby the valve is actuated by the differential in such pressures. The pressure of the spring 30 is added to the well liquid pressure and is predetermined and thus it is obvious that the well liquid pressure must reach a predetermined point before the valve element will be moved downwardly to an unseated position against the pressure of the lifting fluid.

A second valve member 33 is slidable within the axial bore 28 of the valve element 25. The member 33 includes a central shank portion which is formed with longitudinal grooves or channels 34 and the lower end of the member has a valve head 35 threaded thereinto. When the member is in a raised position (Figure 4) the valve head engages a valve seat 36 formed in the lower end of the bore 28 of the outer valve element. When in such position flow through the bore 28 and through the grooves or channels 34 is prevented.

The upper end of the valve member 33 is formed with stop lugs or projections 37 to prevent downward displacement of the member through

the bore 28 of the element 25. If desired, this member may have a valve head at its upper end to prevent reverse flow through the bore 28. The valve member 33 is urged downwardly toward an unseated position by a coil spring 38 which is disposed within the larger spring 30 and which has its lower end engaging the upper end of the member. The upper member of the spring 38 is disposed within an annular groove 39 provided in the lower surface of the adjusting bushing 32. It will be evident that the spring 38 constantly exerts its pressure to urge the valve member 33 downwardly, thereby tending to unseat the valve head 35 from the seat 36 at the lower end of the valve element 25. The spring 38 is of a predetermined pressure so as to control the differential which must be built up across the valve member 33 in order to open the same, as will be hereinafter explained.

Both the outer valve element 25 and the inner valve member 33 are operable by the pressure differential thereacross and the particular differential which is necessary to actuate each is determined by the pressure of the respective springs 30 and 38. It is desirable that the spring 30 which acts upon the outer valve element 25 be of a lighter pressure than the spring 38 which acts upon the inner valve member 33 and the operation will be described with the springs so constructed. However, it is pointed out that under certain conditions it may be more desirable to make the spring 30 the stronger spring, with the spring 38 lighter in pressure.

In the operation of the device, said device is connected to the well tubing as shown in Figure 1 and the lifting fluid is introduced into the annular space between the tubing and the casing, this lifting fluid being at a predetermined or known pressure. For the purposes of this description, it will be assumed that the pressure in the annular space is to be maintained at 300 pounds. It will further be assumed that the pressure of the spring 30 is 100 pounds, while the pressure of the spring 38 is 150 pounds. With no liquid column or pressure within the well tubing, the 300 pounds pressure of the lifting gas in the casing will act through the inlets 23 against the lower ends of the valve element 25 and valve member 33 to hold both of these valves in a seated or closed position, as shown in Figure 4.

As the well liquid column builds up within the tubing 11, the pressure of this liquid column will act upon the upper ends of both valve element 25 and valve member 33, this pressure being added to the springs 30 and 38 which are tending to move these parts toward an open or unseated position. Since the heavier spring 38 has a pressure of 150 pounds, as soon as the well liquid pressure reaches 151 pounds which added to the spring makes a total of 301 pounds, the inner valve element 33 is moved downwardly to an unseated position, whereby the lifting fluid from exteriorly of the housing may flow upwardly through the bore 28 of the valve 25 and into the well tubing. Almost immediately the admission of this lifting fluid which has a pressure of 300 pounds will act to permit the spring 30 to immediately open the outer valve member 25, whereby both inner and outer valves are open, as shown in Figure 2. Opening of both valves permits a large volume of the lifting fluid to enter the well tubing and to move the liquid column upwardly therein. This large volume is necessary and desirable in order to start the fluid moving toward the surface and obviously upward movement of flow of the well liquid will lighten the

load, with the result that the pressure acting against the upper ends of the valves gradually decreases.

When the load or pressure within the well tubing is decreased to less than 200 pounds, then the outer valve element 25 will be again moved upwardly to its seated position because the lifting fluid pressure acting against its lower end will be greater than the combined pressure of the well liquid or load in the tubing and the spring 30. As soon as the outer valve element 25 closes, a continued admission of lifting fluid occurs through the channels 34 of the inner valve member 33 but this continued admission is of a lesser volume. As soon as the liquid column has been moved and is in motion under the impetus of the originally large volume, only a lesser volume is necessary to continue the lifting of said column. The inner valve 33 remains in an open position until the pressure or load within the well tubing has been reduced below 150 pounds, whereby this pressure or load combined with the spring 38 is not sufficient to hold the inner valve open against the 300 pounds lifting fluid pressure. When this occurs the inner valve closes, the parts moving to the position shown in Figure 4. They remain so until such time as the liquid column again builds up to re-open both valves, then successively close them in the manner above described.

It will be obvious that the device provides an efficient means for lifting or raising the well liquids within the tubing. Upon initial operation, both valves are open so as to admit a large volume of lifting fluid which is needed to start the well liquids moving upwardly toward the surface; after the well liquid column is in motion and a lesser volume of lifting fluid is required, the outer valve closes while the inner valve remains open until such time as the lifting of the liquids is complete.

Under certain conditions it may be desirable to admit only a small volume of lifting fluid at the start and then increase such volume and by reversing the springs, that is, placing the stronger spring on the outer or large valve and the weaker spring on the smaller or inner valve, this could be accomplished. Also it may be desirable to further vary the volume throughout the operation of the device and this could be readily done by adding one or more telescoping valves to the assembly, with each valve having a different strength spring. With such arrangement all valves would open at the start of the operation and then would successively or progressively close to reduce the volume of admitted lifting fluid as the load lightened within the well tubing. As has been stated, the device is described as controlling the admission of a lifting fluid into a well tubing but it will be apparent that the telescoping valve arrangement with the variation in spring strengths would make it possible for the device to control the admission of any fluid in a device capable of operating the telescoping valves by a differential in pressure.

The device may be modified so as to employ one of the valves as a relief or stabilizing valve to prevent the lifting fluid pressure exteriorly of the device from exceeding a certain point. It might be noted that where the well casing is open to the formation, formation pressure might be added to the lifting fluid pressure to build up this pressure beyond the 300 pounds which it is desirable to maintain. It will be readily understood that as the lifting fluid pressure in the

casing is permitted to reach an excessive pressure, a valve member, dependent for its operation upon pressure differentials might be rendered inoperative. For example, if the lifting fluid pressure in the casing built up to 600 pounds and a 100 pound spring was acting on the valve element, the well liquid pressure would have to build up in excess of 500 pounds in order to actuate the valve. Well conditions might be such that 500 pounds could never be built up in the well tubing and, therefore, in wells where excess formation pressure may enter the casing, it is desirable to provide a relief or stabilizing valve which will prevent the casing pressure from exceeding a predetermined point.

In Figure 6 the device is shown to operate with the inner valve member 33 controlling the admission of the lifting fluid and the outer element 25 functioning solely as a relief or stabilizing valve. When using the device in this manner, the outer valve element 25 is inverted, that is, the valve head 26 is disposed within the bore 20 of the housing 15 and is adapted to seat against an annular valve seat 24a which is provided at the upper end of the coupling 16 surrounding the upper portion of the bore 16a of the said housing. Manifestly, in this case, the outer valve element 25 will seat to close the bore 16a upon a downward movement thereof.

Assuming that the lifting fluid pressure is to be maintained at 300 pounds, the spring 30a acting to hold the valve element 25 seated in Figure 6 will be set at 325 pounds. Under such condition, with substantially no pressure in the well tubing, which will be the condition following the lifting of a liquid column immediately following operation of the inner valve element 33, the lifting fluid pressure must be greater than 325 pounds in order to open the valve element 25. If the lifting fluid pressure is excessive then at that point, the valve 25 would open to relieve this pressure and permit its escape into the well tubing, whereby the pressure exteriorly of the valve device will be maintained at its desired point.

In this case, the inner valve member 33 functions strictly as a single differentially operated valve and its spring 38 is set for any desired operating condition. Assuming that the spring is set at 150 pounds, building up of the well tubing pressure beyond 150 pounds will open the valve member 33 and admit fluid to lift the well liquids. If the load in the well tubing is lightened sufficiently to reduce the pressure below 150 pounds, the valve 33 will be closed to shut off further flow. It is at this time that the outer valve 25 will function to relieve an excessive pressure in the well tubing if such excessive pressure is present. However, if the pressure in the casing exteriorly of the device never exceeds the desired pressure, the outer valve 25 will never come into operation. Therefore, it is strictly a relief or stabilizing valve which will function to prevent the pressure in the casing from building up to an excessive point which might interfere with the operation of the inner valve member 33.

It is pointed out that in the form shown in Figure 6 it would be possible to employ two telescoping valves arranged in the manner shown in Figures 2 to 4 within an outer relief or stabilizing valve so that the change in volume advantage could be had along with the relief valve arrangement. The telescoping mounting of the valves makes it possible to provide a very simple and compact structure which facilitates manufac-

ing and assembly procedures. As has been pointed out, the valves have been shown with a valve head only on one end thereof but if desired, valve heads may be provided at each end of said valve elements.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A flow control device for controlling the admission of a pressure fluid into a flow line including, a housing having a flow passage which has one end communicating with the flow line and its opposite end communicating with the source of pressure fluid, a valve seat in said passage, a tubular valve element mounted in the passage and movable into and out of engagement with said seat, said valve element having one end exposed to the pressure of the pressure fluid with its opposite end exposed to the pressure in the flow line, whereby the valve element is actuated by the differential in the pressures acting on opposite sides thereof, resilient means acting on one side of the valve element for controlling the pressure differential which is necessary to actuate the valve element, and a second valve member mounted within the tubular valve element for controlling the flow through said element and having one end exposed to the pressure of the pressure fluid and its opposite ends exposed to the pressure in the flow line, whereby the member is actuated by the differential in such pressures, and a second resilient means acting on the valve member and of a different strength than the first resilient means for controlling the differential which is required to actuate the valve member.

2. A flow control device as set forth in claim 1, wherein the resilient means are coiled springs of different predetermined pressures.

3. A well flow device for controlling the admission of a pressure fluid into a well conductor and including, a housing having a flow passage for establishing communication between the interior and exterior of the housing, a plurality of valve elements in said passage for controlling flow through said passage, each element having one end exposed at all times to the pressure exteriorly of the well conductor and its opposite end exposed to the pressure interiorly of said conductor, whereby said valve elements are actuated by the differential in the pressures acting thereon and individual means associated with each valve element for controlling the differential across the valve required to actuate said element, each valve element being of a different size than the other elements whereby the elements permit a varying volume of flow, and each element being set to be actuated by a different pressure differential thereacross, whereby the elements are progressively actuated.

4. A well flow device for controlling the admission of a pressure fluid into a well conductor and including, a housing having a flow passage for establishing communication between the interior and exterior thereof, a tubular valve element in said passage movable to open and closed positions and having one end constantly exposed to the pressure exteriorly of the conductor and its opposite end exposed to the pressure interiorly of said conductor, whereby it is actuated by the differential in such pressures, a second valve member

slidable within the valve element movable to open and closed positions and having one end constantly exposed to the pressure exteriorly of the conductor with its opposite end exposed to the pressure interiorly of the conductor, whereby said second member is also actuated by the differential in pressures acting thereon, means associated with the valve element for controlling the pressure differential thereacross required to actuate the same, and means associated with the valve member for controlling the pressure differential thereacross required to actuate said member.

5. A well flow device as set forth in claim 4, wherein the valve element and valve member are of different sizes, whereby when in an open position each permits a volume of flow different from the volume permitted by the other.

6. A well flow device as set forth in claim 4, wherein the means associated with the valve element is of a greater or lesser strength than the means associated with the valve member, whereby the element and member are actuated at various pressure differentials.

7. A well flow device as set forth in claim 4, wherein the controlling means associated with the valve element and valve member are springs acting on said element and member, said springs being of different strengths, whereby the element and member are actuated at various pressure differentials.

8. A well flow device for controlling the admission of a pressure fluid into a well conductor and including, a housing having a flow passage for establishing communication between the interior and exterior thereof, a tubular valve element in said passage movable to open and closed positions and having one end exposed to the pressure exteriorly of the conductor and its opposite end exposed to the pressure interiorly of said conductor, a second valve member slidable within and entirely through the valve element movable to open and closed positions and having one end exposed to the pressure exteriorly of the conductor with its opposite end exposed to the pressure interiorly of the conductor, a spring acting on that side of the valve element which is exposed to the pressure interiorly of the well conductor, and a spring of different strength acting on that side of the valve member which is exposed to the pressure interiorly of the tubing, said springs functioning to control the pressure differentials necessary to actuate said element and said member.

9. A well flow device as set forth in claim 8, wherein the valve element is of a larger area and when open permits a larger volume of flow through the passage than the valve member.

10. A well flow device for controlling the admission of a pressure fluid into a well tubing and including, a housing having a flow passage for establishing communication between the interior and exterior of the tubing, a main valve element in said passage for controlling flow through said passage and having one end exposed to the pressure exteriorly of the tubing with its opposite end exposed to the pressure interiorly of the tubing, whereby the valve is operated by a differential between such pressures, and a stabilizing valve also mounted in the housing and actuated by the pressure exteriorly of the tubing to maintain said exterior pressure substantially constant.

11. A well flow device for controlling the admission of a pressure fluid into a well tubing and including, a housing having a flow passage for establishing communication between the interior

11

and exterior of the tubing, a main valve element in said passage for controlling flow through said passage and having one end exposed to the pressure exteriorly of the tubing with its opposite end exposed to the pressure interiorly of the tubing, whereby the valve is operated by a differential between such pressures, a relief valve also mounted within the housing and normally held in a closed position by a flexible means of predetermined pressure, the relief valve being exposed to the pressure exteriorly of the tubing, whereby when such pressure exceeds that of the flexible means the relief valve is opened to reduce said pressure exteriorly of the tubing to the predetermined point as controlled by the pressure of the flexible means.

12. A well flow device for controlling the admission of a pressure fluid into a well conductor and including, a well conductor, a housing adapted to be connected to said conductor and having a flow passage for establishing communication between the interior and exterior of the conductor, a valve seat within the housing, a tubular relief valve element adapted to engage said seat to shut off flow past the seat, said relief valve being exposed to the pressure exteriorly of the conductor and being moved to an open position when said pressure exceeds a predetermined point, and a co-axial main valve member mounted within the relief valve element and extending entirely therethrough for controlling flow through said element and through the housing into the conductor.

13. A well flow device as set forth in claim 8, wherein the main valve member has one end exposed to the pressure exteriorly of the tubing and its opposite end exposed to the pressure interiorly of said tubing, whereby said valve member is actuated by the differential in such pressures.

14. A well flow device for controlling the admission of a pressure fluid into a well tubing and including, a well tubing a housing mounted on said tubing and having a flow passage for establishing communication between the interior and exterior of the tubing, a valve seat within the housing, a tubular valve element adapted to en-

12

gage said seat to shut off flow past the seat, said valve having opposite ends exposed to the pressure exteriorly and interiorly of the tubing, a co-axial valve member mounted within the valve element and extending entirely therethrough for controlling flow through said element and through the passage of the housing, said valve member having one end exposed to the pressure exteriorly of the tubing and its opposite end exposed to the pressure interiorly of the tubing, a spring acting on the tubular valve element and adding its pressure to the pressure interiorly of the tubing, and a spring acting on the valve and adding its pressure to the pressure interiorly of the tubing, said springs being of predetermined strengths and functioning to control the pressure differential which is required to actuate said valve.

15. A well flow device including, a well conductor, a housing connected on said conductor and having a flow passage therein for establishing communication between the interior and exterior of said conductor, a relief valve mounted within the housing actuated to admit pressure from exteriorly of the housing and conductor to the interior thereof when the exterior pressure exceeds a predetermined point, and a main valve member within the housing operable independently of the relief valve, said main valve member having one end exposed to the pressure exteriorly of the conductor and its opposite end exposed to the pressure interiorly thereof, whereby said valve is actuated by the differential in such pressures.
